UNITED STATES PATENT OFFICE

2,043,868

THROTTLE CONTROL MECHANISM

Edward J. Sampson, Corpus Christi, Tex.

Application June 17, 1935, Serial No. 27,120

5 Claims. (Cl. 192—.01)

My invention relates to improvements in throttle controls for internal combustion engines.

By way of explanation, the internal combustion engines of tractors are usually equipped with a 5 throttle control including a hollow rock shaft set-table in opposite directions to increase or diminish the flow of fuel to the engine, a spark control shaft extending through the fuel control shaft, and hand levers cooperating with a detent segment for setting said shafts. In starting the 10 engine with this form of control, it is difficult to gauge the exact amount of fuel required to start the engine and overcome the inertia of the tractor when the clutch is engaged without stalling the 15 engine on the one hand, or, on the other hand, racing the same with consequent damage to the clutch facings, oil dilution, and wear and tear on the mechanism in general.

With the foregoing in mind, the primary object 20 of my invention is to equip a gasoline engine, having the type of control above specified, with an auxiliary control operative under control of the clutch shifting mechanism of the tractor to rock the fuel control shaft in the proper degree 25 to admit to the engine the exact quantity of fuel required to start the engine and overcome the inertia of the tractor.

Another object is to provide means for presetting the auxiliary control to vary, under different operating conditions, the feed of fuel.

Another object is to provide an auxiliary control for the purposes specified which permits independent setting of the fuel control shaft by its hand lever.

35 A further object is to provide for a variable setting of the fuel control shaft to obtain proper idling speeds of the engine under different operating requirements.

Other and subordinate objects will presently 40 appear and the nature of my improvements will be readily understood from a reading of the following description and claims in conjunction with the accompanying drawing.

In said drawing:

45 Figure 1 is a perspective view of a part of the engine and fuel supply tank of the tractor and illustrating my improved auxiliary control applied to the engine.

50 Figure 2 is a fragmentary view in vertical transverse section taken on the line 2—2 of Figure 1 and drawn to an enlarged scale.

Figure 3 is a similar view of a modification of the invention.

55 Figure 4 is a view in transverse section taken on the line 4—4 of Figure 3 and

Figure 5 is a view in side elevation of a further modification of the invention.

With reference to the drawing, the numeral 1 designates a portion of the engine of a tractor, 2 the fuel tank therefor, and 3 the steering mechanism all shown in dot and dash lines. The numeral 4 designates a hollow fuel control rock shaft connected at one end, in a manner well understood and not requiring explanation herein, to the usual carburetor, and having its opposite end mounted in a bracket 5 bolted to the engine casing as at 5' and having a detent segment 6 thereon. Adjacent the segment 6 the shaft 4 has mounted thereon a hand lever 7 for cooperation with said segment and by means of which the shaft is set in opposite directions to throttle opening and closing positions respectively. Within the shaft 4 is the usual spark control shaft 8 adapted to be rocked by the hand lever 9 to control the spark in a manner not important to the present disclosure. The numeral 10 designates the clutch control lever vertically movable, in this instance, in opposite directions to clutch engaging and disengaging positions, respectively, and tensioned by a suitably connected spring 11 for movement to engaging positions.

According to my invention, in its preferred embodiment, the clutch control lever 10 is operatively connected to the fuel control rock shaft 4 as follows. An annular collar 12 is removably secured upon the shaft 4 by means of a screw 13 passing through said collar. A pair of blocks 14 are clamped upon opposite sides of said collar by means of bolts 15, wing nuts 16 upon the outer ends of said bolts, a plate 17 disposed upon the upper edge of one of said blocks and through which the bolts 15 pass, and tension springs 18 interposed between the wing nuts 16 and the plate 17. The blocks 14, the plate 17, bolts 15 and nuts 16 comprise a rocking unit for frictionally engaging the collar 12 to rock the shaft 4. The plate 17 extends beyond the ends of the blocks 14 one of its extended ends being provided with a series of apertures 19. A rod 20, having a hooked end 21 secured in one of said apertures 19 by a cotter pin 22 and its other end passing through a plate 23, clipped to the clutch control lever 10, as at 24, connects the plate 17 to said lever. A tension spring 25 interposed between said plate 23 and a collar 26 fast on the end of the rod 20 provides a connection between said rod 20 and lever yielding when the lever is moved downwardly to its clutch disengaging position. A collar 27 fast on the rod 20 immediately above the plate 23 provides for rocking the shaft 4 by upward move-

ment of the lever 10 to clutch engaging position. A stop 28 in the form of a set screw mounted in a bracket 29, fixed to the engine casing as at 30, overhangs the opposite end of the plate 17 and 5 limits movement of the shaft 4 by movement of the lever 10 to clutch disengaging position. A set screw 31 mounted upon the segment 6 limits movement of the shaft 4 to throttle closing position by engagement with the hand lever 7.

10 Referring to the operation of the above-described form of my invention, the clutch control lever 10 is first moved to clutch disengaging position thereby rocking the blocks 12, the parts carried thereby, and the fuel control shaft 4 towards 15 throttle closing position until the plate 17 engages the set screw 28. The hand lever 7 is then moved against the set screw 31 to rock the fuel control shaft 4 independently in proper degree to secure the desired idling speed of the engine 20 as determined by adjustment of the set screw 31. Obviously upon release of the clutch control lever 10 the fuel control shaft 4 will be rocked in a reverse, i. e. throttle opening direction, in fixed 25 degree which degree may be varied by means of the set screw 28 to regulate the feed of the fuel in accordance with the exact requirements for starting the engine and overcoming the inertia 30 of the load imposed thereon when the clutch is engaged. The feed may be increased or diminished by independently rocking the fuel control shaft 4 through the medium of the hand lever 7, the spring 25, as will be clear, permitting a full 35 downward stroke of the lever 10 and movement in less degree of the blocks 12, rod 20, and parts carried thereby. The degree of movement of the blocks 12 may be varied by positioning the end 21 of the rod 20 in different apertures 19 in the plate 17.

In the modification shown in Figure 3 a lever 40 32 is used in lieu of the previously described blocks 12, said lever being loosely mounted on the fuel control shaft 4 and frictionally clutched to the same as follows. A pair of friction discs 33 are loosely mounted on said shaft upon opposite sides of said lever said discs being formed of any suitable, preferably fibrous, material. A disc 34, complementary to one of said discs 33 is secured upon the shaft 4 in frictional engagement with said disc 33 by means of a set screw 34' 45 threaded into a hub 35 on said disc 34. A sleeve 36 having an end flange 37 complementary to the other disc 33 is loosely mounted on the shaft 4 with one end thereof projecting into a sleeve 38 50 adjustably mounted on said shaft 4 by means of a set screw 39. A tension spring 40 is interposed between said sleeve 38 and flange 37. The sleeves 36 and 38 are splined to each other by means of a slot 41 in the sleeve 36 and a bolt 42 in the sleeve 38 projecting into said slot. The tension 55 spring 40, as will be clear, causes the discs 33, 34, and flange 37 to frictionally clutch the lever 32 to the shaft 4 and this clutching relation may be varied by adjustment of the sleeve 38 longitudinally of the shaft 4.

60 In Figure 5 there is shown a modified form of the invention for yieldingly connecting the rod 20 to a clutch control rod endwise movable. This connection takes the form of a bell crank 43 through one end of which the rod 20 passes and 65 is yieldingly connected thereto in the same manner as described with reference to the preferred form of the invention. The opposite end of the bell crank 43 is connected to the endwise movable shaft 44 by means of collars 45, a cotter pin 46 bearing against one of the collars 45 and

70 a tension spring 47 interposed between the other collar 45 and a collar 48 fixed against movement under the action of said spring by a cotter pin 49. The arrangement of the described connecting parts is such that the clutch control shaft 44 is 75 yieldingly movable in opposite directions relative to the rod 20.

The foregoing is a detailed description of a preferred form of my invention and certain modifications thereof, but it is to be understood that other modifications may be resorted to without departing from the inventive concept disclosed nor the scope of the appended claims.

What I claim is:

1. The combination with a throttle control rock shaft of an internal combustion engine, said shaft being manually settable in opposite directions to throttle opening and closing positions, respectively, and a clutch control member movable in opposite directions to clutch engaging and disengaging positions, respectively, of a rocking unit frictionally clutched to said shaft to rock the same and permit independent rocking of said shaft, and means for imparting a limited and variable degree of rocking movement to said unit by operation of said member to clutch engaging position.

2. The combination with a throttle control rock shaft of an internal combustion engine, said shaft being manually settable in opposite directions to throttle opening and closing positions, respectively, and a clutch control member movable in opposite directions to clutch engaging and disengaging positions, respectively, of a rocking unit frictionally clutched to said shaft to rock the same and permit independent rocking of said shaft, and means for imparting a limited and variable degree of rocking movement to said unit by operation of said member to clutch engaging position, and including operating connections between said unit and member yielding during movement of the latter to clutch disengaging position, and a settable stop for limiting movement of said unit by operation of said member to clutch disengaging position.

3. The combination with a throttle control rock shaft of an internal combustion engine, said shaft being manually settable in opposite directions to throttle opening and closing positions, respectively, and a clutch control lever movable in opposite directions to clutch engaging and disengaging positions, respectively, and tensioned for movement to engaging position, of a settable stop for limiting movement of said shaft in throttle closing direction, a rocking unit frictionally clutched to said shaft to rock the same and permitting independent setting of said shaft, and means for imparting a limited degree of movement to said unit by operation of said lever to clutch engaging position and including operating connections between said lever and unit yielding in the direction of movement of said lever to clutch disengaging position, and a settable stop for limiting movement of said unit by movement of said lever to disengaging position.

4. The combination with a throttle controlling rock shaft of an internal combustion engine, said shaft being manually settable in opposite directions to throttle opening and closing positions, respectively, a setting lever for said shaft, and a clutch control lever movable in opposite directions to clutch engaging and disengaging positions, respectively, and tensioned for movement to engaging position, of means for imparting a limited variable degree of rocking movement to

- said shaft in a throttle opening direction by movement of said lever to clutch engaging position and permitting independent setting of said shaft said means comprising a collar fast on said 5 shaft, a pair of opposed blocks yieldingly clamped to said collar to frictionally engage the latter, operating connections between said blocks and lever including a rod, a connection between said rod and lever yielding during movement of the 10 latter to clutch disengaging position, a variable connection between said rod and blocks for altering the throw of said blocks relative to that of said lever, and a settable stop for limiting movement of said blocks by movement of said lever to 15 clutch disengaging position.
5. The combination with a throttle controlling rock shaft of an internal combustion engine, said shaft being manually settable in opposite directions to throttle opening and closing positions, 20 respectively, a setting lever for said shaft, and a clutch control lever movable in opposite directions to clutch engaging and disengaging posi-
- tions, respectively, and tensioned for movement to engaging position, of means for imparting a limited variable degree of rocking movement to said shaft in a throttle opening direction by movement of said lever to clutch engaging position and permitting independent setting of said shaft said means comprising a collar fast on said shaft, a pair of opposed blocks yieldingly clamped to said collar to frictionally engage the latter, operating connections between said blocks and 10 lever including a rod, a connection between said rod and lever yielding during movement of the latter to clutch disengaging position, a variable connection between said rod and blocks for altering the throw of said blocks relative to that of 15 said lever, a settable stop for limiting movement of said blocks by movement of said lever to clutch disengaging position, and a settable stop for limiting movement of said shaft by said setting lever in a throttle closing direction. 20

EDWARD J. SAMPSON.
